COMPARTMENTED ONE-PIECE BILLFOLD CONSTRUCTION PROVIDED WITH WINDOW OPENING

Louis Lampert, Chicago, Ill.

Application December 6, 1945, Serial No. 633,123

1-Claim. (Cl. 150—32)

1

This invention relates to an improved wallet, or billfold, and has for one of its principal objects the provision of a device of the class described, which will enable the user to more conveniently carry money, particularly paper money, while at the same time providing adequate insurance for its safe retention.

One of the important objects of this invention is the provision of a wallet, or money carrying device, particularly adapted for handling bills, or paper money, wherein the bills, when inserted in the wallet, or billfold, and after the wallet, or billfold, is folded in the usual manner, will remain on the outside face of the wallet, or billfold, so as to be readily accessible to the user.

Another and further important object of the invention is the provision of a billfold, for carrying paper money, wherein bills of smaller denomination can be safely carried on the outer face, or sides, of the billfold, for ready access, while at the same time bills of larger denominations can be stored in an interior compartment, rendering the same less accessible and also enabling the user to differentiate between said large and small bills, so that mistakes will be avoided.

Other and further important objects of the invention will be apparent from the disclosures in the accompanying drawings and following specification.

The invention, in a preferred form, is illustrated in the drawings and hereinafter more fully described.

In the drawings:

Figure 1 illustrates the two portions of the improved wallet, or billfold, of this invention, showing the same in pre-formed blanked-out shape.

Figure 2 is a view of the large blank of Figure 1 showing the same folded in preliminary fashion and illustrating one method of assembly.

Figure 3 shows the complete wallet, or billfold, lying flat and with paper money, or the like, therein in the proper compartments and retaining means.

Figure 4 shows the completed wallet, with money therein, folded and ready for use.

Figure 5 illustrates the reverse face of the billfold, shown in Figure 4.

As shown in the drawings:

The reference numeral 10 indicates, generally, the blank from which the improved wallet, or billfold, of this invention is constructed and obviously it may be of leather, impregnated fabric, plasticized cloth or other material, or any synthetic material or combination thereof, depend-

2

ing upon the manufacturing facilities and the desires of the purchasing public.

The blank 10 includes a main portion which forms the back of the wallet, and integral therewith is another portion 12, which forms the front portion of the billfold.

The back portion 10 has an integral end-extension 14 and the end opposite this extension projects beyond the portion 12, as shown at 10a, and terminates in sidewise tabs 16 and 17, having a projecting edge 18 therebetween.

One side of the body 12 has an integral longitudinal tab or edge 20 which, however, terminates short of one end of this portion 12, all as best shown in Figures 1 and 2.

A slit 22 is made in the body portion 16 at the point shown in Figures 1 and 2, and four slits are cut into the body portion 12, these being indicated at 24—26—28 and 30. The slits 24—26 and 28 are of approximately the same length as the slit 22, while the slit 30 is longer. The body portion 10 has an integral edge portion 32 similar to the edge 20 of the body portion 12, although, somewhat longer.

The method of assembly of the device is illustrated in Figure 2 and this shows the end element 14 bent upwardly and the end of the main body portion 10 also bent upwardly along lines corresponding with the ends of the body portion 12 and the edge 32 of the body portion 10 is also bent upwardly. At the same time, the tabs 16 and 17, are similarly bent upwardly along the dash-lines shown in Figure 1 and the edge 18 is likewise bent upwardly. The edge portion 20 is folded inwardly about the dash line shown in Figure 1 and the edge portion 32 is folded as illustrated. The edge 20 of the body portion 12 is first folded downwardly onto the portion 12 and cemented into position forming a double thickness edge to insure against wear. The edge 32 is likewise folded over and cemented.

The extension 14 is then folded into position over the back of the body portion 12 and the tab integral with this extension 14 inserted through the slit 30. It will be noted that the tab has inwardly extending slits 40 adjacent its ends which enable of a locking relationship with the ends of the slit 30. This extension 14 is then cemented into position.

The extension 10a of the main body portion 10 is then folded into position over the corresponding end of the body portion 12 and the tab 16 is inserted in the slit 24 in the body portion 12 after the extension 16 has been folded around

that edge of the body portion 12, which does not include the edge portion 20.

The other tab 17 is then brought around the back of the substantially completed wallet, or billfold, inserted in the slit 22 in the body portion 10, and cemented into position.

The strap 42 is then placed in position by passing it through the two slits 26 and 28 and then out through the slit 44 after which it is brought around the front portion 12 of the wallet, or billfold. The strap 42 is provided with snap fastener elements 46 and 48 and these snap elements 46 and 48 are brought together in a customary manner, thereby joining the strap into a retaining element for bills 50 as best shown in Figures 3 and 4. The snap element can obviously be readily loosened so that bills can be placed in the wallet, or billfold, after which it is folded into the position shown in Figures 4 and 5 with one end of the contained bills in the pocket formed by the turned over element 10a.

In this manner the retained bills are very readily accessible and all that is necessary for the user to dispense a bill is to keep the wallet, or billfold, in its folded position, grasp the juxtaposed ends in one hand without touching the bill and withdraw the bill from the billfold, with the other hand. The bills will come off singly and readily. At the same time, a pocket is provided for other bills, such as bills of larger denominations, this pocket being formed by the folded elements 10 and 12. This pocket is closed at the ends so that bills placed therein will not be liable to be lost.

It will be seen that herein is provided a money container, which embodies an entirely new principle, in that some or all of the contained bills may be carried on the outside thereof, providing for ready access thereto, while at the same time, the money is securely retained in position, one end being under the strap 42 and the other end being tucked in the pocket 10a. The money can be withdrawn from the wallet, or billfold, without unfolding it and the bills can be withdrawn singly or in groups as desired. Other bills may be carried in the pocket of the wallet, or billfold, and this is preferably used to contain bills of larger denominations, whereby the possibility of confusion and loss is avoided. Money may be withdrawn from the wallet, without removing the same from the user's pocket, which provides a security feature sometimes greatly to be desired.

In the event that bills of more than one denomination are held in the billfold on the outer face thereof, and beneath the strap 42 and the user desires to withdraw bills other than those on top, this can easily be done by unfolding the billfold into the position shown in Figure 3, whereupon

bills beneath the topmost one can readily be withdrawn in an obvious manner.

Additional pockets can obviously be built into the billfold of this invention for containing identification cards, or the like, and a coin container may also be included, if desired.

I am aware that many changes may be made and numerous details of construction varied throughout a wide range without departing from the spirit of the invention, and I therefore do not purpose limiting the patent granted hereon otherwise than as necessitated by the prior art.

I claim as my invention:

A foldable billfold formed from a single blank of flexible material and including an inner wall, an outer wall folded upon said inner wall about a longitudinal medial line, to form a receptacle for bills, an end extension at one end of said inner wall folded upon said folded outer wall, means to secure said extension to the outer wall, a second end extension at the other end of said inner wall, said second extension being of a width equal to the width of the inner wall, sidewise tabs on said second extension, one of said tabs being foldable about the longitudinal line of fold and having means secured to said inner wall, the other of said tabs being foldable over the free longitudinal edge of the outer wall and having means secured to said outer wall, said second extension together with the outer wall thus forming a pocket having a width substantially equal to that of the billfold and of a depth sufficient to receive end portions of other bills, the rest of said other bills being exposed to view, a strap encircling the opposite end of the bill fold remote from the pocket and snap fasteners for releasably fastening the strap ends, whereby the exposed bills are securely retained in position on the outer wall, with their end portions being retained in the pocket and under the strap, respectively.

LOUIS LAMPERT.
